RECIPROCATING DIE PRESS

Frank E. Stratton and Horatio V. Hall, Beverly,
Mass., assignors to United Shoe Machinery
Corporation, Flemington, N. J., a corporation
of New Jersey

Application March 29, 1949, Serial No. 84,176

10 Claims. (Cl. 164—25)

1

This invention relates to presses, and more particularly to presses of the type commonly referred to as clicking machines, employed for cutting shoe part blanks from leather or fabric.

In such machines, as heretofore constructed, use has been made of mechanism including a platen or cutting block for supporting sheet material to be operated upon, a freely movable die which can be located upon the material, and a beam movable over the block into position above the die, together with means for causing relative movement of the block and beam toward each other to force the die through the material in order to produce a blank. In the past, various mechanisms have been devised for effecting the relative movement between the cutting block and the beam, and several of them have been highly successful from a commercial standpoint.

An object of the present invention is to provide an improved machine of the type referred to in which the mechanism for causing relative movement between the beam and cutting block is particularly effective in its operation to the ends of producing accurate cutting of blanks with low power consumption and low vibration transmission to the immediate surrounding of the machine, while, at the same time, one which will be easy and safe to operate as well as economical to service.

In view of this, the invention as herein illustrated provides a press in which there is a platen for supporting sheet material and a cutting die, and a beam movable across the platen into operative position over the die, together with means for moving the platen toward and away from the beam and for effecting a rolling movement of the platen along the beam progressively to force the die through the material in producing a blank. Preferably, and as shown, the movement of the platen is effected partly by means of toggles which are arranged to raise the platen toward the beam, there being additional means, herein illustrated as a cam controlled platen constraining member, cooperable with the toggles to guide the platen in its rolling movement. Preferably, and as shown, there are also provided manually operable starting means associated with the beam and so constructed and arranged that it is necessary for the operator to use both hands in initiating a power operation of the machine, thus insuring that his hands are in a safe position during operation of the platen. As disclosed herein this mechanism takes the form of two manual controls, operation of both of which is required to close an electric circuit through a solenoid operable to initiate a power operation of the toggles. Repetition of a power operation is prevented by means of electrical devices until both of the manual controls have been released, thus preventing unauthorized jamming of the safety mechanism.

60

2

Means are also provided for adjusting the beam heightwise of the platen to accommodate dies of various heights, and for arresting lateral movement of the beam across the platen upon initiation of a power operation. There is also provided a novel form of platen comprising a cutting block provided with a curved cutting surface for co-operating with the beam in progressively forcing a die through the material to be operated upon in producing a blank.

These and other objects and features of the invention are disclosed in the following specification and in the accompanying drawings and are pointed out in the appended claims.

Fig. 15 is a plan view partly in section illustrating the beam brake; and

Fig. 16 is a wiring diagram illustrating the electric circuit employed in the machine.

The drawings illustrate a clicking machine operable with freely movable cutting dies for producing blanks from sheet material such as leather or fabric.

As shown in Fig. 1 the machine comprises a platen 10 adapted to support upon its upper face sheet material 12 and a cutting die 14 located upon the material with its cutting edge down. Above the platen is located a beam 16 secured

to a vertically extending post 18 positioned at one side of the platen and rotatably mounted in the frame 20 of the machine. The beam is movable by means of a handle 22 about the axis of the post and across the platen 10 into operative position above the die located upon the sheet material. Operatively connected to the platen is mechanism including toggles 24 for moving the platen upwardly toward the beam to present the die into engagement with the beam, for rolling the platen along the beam in effecting progressive penetration of the cutting edge of the die through the work to produce a blank, and for returning the platen to a rest position.

The platen 10 comprises a substantially rectangular casting 26, the upper portion of which is dished to form a recess 28 within which is positioned a cutting block 29. Preferably the cutting block is composed of a metal core 30 covered with a layer 31 of plastic such as rubber or rubber and fiber material bonded to the case. The block has oppositely curved faces corresponding in curvature to that of the bottom face of the recess, each face being a portion of a cylinder of about a sixteen foot radius. The curvature of the block is such as to facilitate the presentation of the work to the beam and to prevent creeping of the die during the cutting operation as the platen is rolled along the face of the beam. The block can be positioned with either of the faces located in the recess and is held in position against lateral movement by metal strips 32 which engage the block 29 and the casting 26 and are held in position by screws 34. The block is thus provided with two alternately useable work supporting faces. When one face becomes worn the block is reversed presenting a fresh face uppermost.

The lower portion of the platen 10 and most of the operating mechanism of the machine are located within the frame 20 which comprises a hollow box-like casting, the upper portion of which is open to permit heightwise and rolling movement of the platen. The upper portion of the frame is provided with an apron 36 surrounding the platen 10 and extending close to the ends of the platen but sufficiently spaced therefrom at the sides to provide a clearance for the platen during its rolling movement.

The platen 10 is supported by four toggles 24 each being located approximately at a corner of the platen. Each toggle 24 (Fig. 6) comprises upper and lower toggle links 40 and 42, respectively, pivotally secured together by pins 44, the upper end of the upper link 40 being pinned to a boss 46 on the underside of the platen and the lower end of the lower link 42 being pivotally mounted in a boss 48 on a bracket 50 forming a part of the frame.

The toggles 24 at each end of the machine are in lateral alignment and are arranged to be operated by two toggle levers 52 each having one end pivotally secured to a lower toggle link 42 at 54, and carrying a pin 56 supporting a roller 57 slidably mounted in a guide slot 58 formed in a bracket 60 secured by bolts 62 to the frame.

Outward movement of the toggle levers 52, effective to straighten the toggles, is obtained by means of a cam 64 mounted upon a cam shaft 66 arranged to engage cam rolls 68 positioned upon the inner ends of the pins 56. The toggles are normally urged toward each other and the rolls 68 are maintained in engagement with the cam 64 by means of a coil spring 70 connecting the ends of arms 72 extending from the toggle levers.

The position of the platen during operation of the toggles is partly determined by two platen control levers 74, Figs. 1, 2, 3 and 6, connected to opposite ends of the platen along one side thereof. Each lever 74 is pivotally mounted on a boss 76 on the frame and has an upper end pivotally connected to one end of a link 78 the other end of which is pinned at 80 to a bracket 82 on the underside of the platen. The lower end of each lever 74 carries a roll 84 positioned in the track 86 in a cam 88 mounted on the cam shaft 66. The cam 88 is so designed that during the movements of the toggles the control levers 74 are operated to rock the platen about the pins 44 in such manner as to maintain the platen in tilted position during its movement toward the beam in presenting the work and die to the beam and in effecting a rolling movement of the platen along the beam progressively to force the die through the work.

The cam 64 is so designed that the toggle levers 52 on opposite sides of the machine, operate 180° out of phase with each other. In its rest position the platen 10 is tilted with one side higher than the other and corresponding toggles at the high side are more straightened than those on the low side. Upon rotation of the cam 64 the toggle levers 52 operate further to straighten the toggles 24 on both sides of the machine thus raising the platen. Subsequently, the toggles on the high side of the platen are broken and those on the low side are further straightened to effect a rocking of the platen under the control of the levers 74 after which the toggles on both sides are broken returning the platen to rest with the formerly low side now in raised position.

Means is provided for preventing movement of the platen in an endwise direction to reduce the likelihood of movement of the die along the platen during the cutting operation. To this end the platen is provided at opposite ends with downwardly projecting plates 90 the outer surfaces of which are machined and are adapted to engage hardened buttons 92 located upon the frame. The buttons closely engage the plate during the movement of the platen and serve to prevent endwise play thereof.

The beam 16 is a box-like structure comprising a hollow casting 94 having a U-shaped throat portion 96 at one end partially surrounding the upper end of the post 18, and is clamped to the post by bolts 98 which extend through a cap 100 positioned on the post. To the underside of the beam is secured a metal plate 102 preferably an aluminum alloy to form the striking face of the beam.

The post 18 is mounted for rotation about its axis in a bearing formed by a vertical extension 106 of the frame and a cap 108 clamped to the extension by bolts 110. The post has at its lower end a reduced portion 112 (Fig. 8) rotatably mounted in an externally threaded sleeve 114 positioned within a nut 116 carried by an extension 118 of the frame. Above the reduced portion is a shoulder 120 which rests upon a thrust bearing 122 located at the upper end of the sleeve 114 and arranged to support the weight of the post and beam. Rotation of the sleeve 114 results in the movement of the same up or down relatively to the nut 116 with the consequent result that the post is raised or lowered, thus providing for adjustment of the beam heightwise of the machine. The lowermost end of the post is provided with threads 124 upon

which is positioned a stop ring 126 held against rotation by set screw 128 and arranged to take up the upward thrust of the post.

Conveniently the movement of the sleeve 114 is controlled by a hand wheel 130 (Figs. 1 and 2) arranged to rotate a horizontally extending shaft 132 supported in a bracket 134 secured to the frame. The shaft 132 is operatively connected by gears 136 and 138 to a second shaft 140 carried by brackets 142. The shaft 140 in turn is connected by gears 144 and 146 to a vertical shaft 148. The shaft 148 is mounted on a thrust bearing 150 (Fig. 8) and near its lower end carries a spur gear 152 loosely mounted upon the shaft, its weight being carried by a collar 154 pinned to the shaft. The spur gear is rotated by means of a pinion 156 carried by the shaft and arranged to engage pinions 158 rotatably mounted on a bracket 160, and having teeth arranged to mesh with internal teeth 162 on the spur gear. The spur gear has external teeth 164 which mesh continuously with a gear 166 formed on the upper end of the sleeve 114, the gear 166 being movable with the sleeve heightwise of the spur gear 152.

Rotation of the hand wheel 130 effects rotation of the spur gear 152 which causes the sleeve 114 to turn in the nut 116 thus resulting in the movement of the sleeve heightwise of the nut and corresponding movement of the post 18 and beam 16 in a direction heightwise of the platen.

In order to indicate the appropriate position of the beam 16 heightwise of the platen 10 for operation with dies of different heights, the upper portion of the frame extension 106 is provided with a vertically extending scale 168 (Fig. 1) marked off with divisions representing various die heights. The post is provided with a pointer 170 which upon adjustment of the post heightwise of the frame can be brought into alignment selectively with one or another of the divisions on the scale. The arrangement is such that for each setting of the pointer for a particular die height the beam will be in position to provide for normal movement of the platen of about $\frac{3}{4}$ of an inch upwardly toward the beam and for the height of the particular die being used without penetration of the die into the cutting block. After a rough adjustment is made the post is then further adjusted heightwise of the frame 50 by a small fraction of an inch to position the beam so that the die will penetrate slightly into the cutting block during the operation of the machine.

The cam shaft 66 is supported at its ends in 55 the brackets 60 as shown in detail in Fig. 4. Each end of the shaft 66 is mounted in a ball bearing 172 carried by a sleeve 174 positioned in the bracket 60 and secured thereto by bolts 176. A cap 178 threaded into the sleeve 174 forms a closure for the sleeve.

The cam shaft 66 has a worm wheel 180 (Fig. 5) which is arranged to be driven by a worm 182 on the main drive shaft 184 of the machine. The drive shaft is rotatably mounted in ball bearings 186, 188 and 190, Fig. 5. Bearings 186 which support the outer end of the shaft are carried by a bushing 192 secured to a housing 194 surrounding the worm wheel 180, the housing in turn being bolted to a portion of the machine frame at 196. The bearings 188 are supported in a sleeve 198 carried by the housing 194. The bearings 190 for supporting the inner end of the shaft are carried by a sleeve 200 located in 70 75

a bracket 202 depending from the frame. Loosely mounted upon the ball bearings 204 upon the inner end of the drive shaft is a flywheel 206 arranged to be driven by an electric motor 208 (Fig. 1) by means of a belt 210.

For effecting operations of the drive shaft there is provided a multiple disk type combination clutch and brake assembly 212. This assembly comprises a body portion 214 surrounding the 10 drive shaft adjacent to the flywheel. The body portion is rotatable with the shaft and is arranged for movement axially of the shaft selectively into clutching engagement with the flywheel or braking engagement with the frame of 15 the machine. The body portion has at one end clutch plates 216 keyed to the drive shaft and engageable with plates 218 keyed to the flywheel for connecting the flywheel to the shaft. At the other end of the body portion there are provided 20 brake plates 220 keyed to the drive shaft and engageable with fixed plates 222 carried by bracket 224 positioned in the sleeve 198 and arranged for arresting motion of the shaft at the end of an operation of the machine.

25 The body portion 214 of the assembly is arranged to be shifted into clutch engaging or into braking position by means of an actuating lever 226 (Fig. 5) pivoted on a bracket 228. The upper end of the lever terminates in a yoke 230 engaging trunnions 232 on a ring 234 positioned in a groove 236 in a sleeve 238 forming part of the body portion 214. A coil spring 240 (Figs. 1 and 7) connected to a bracket 242 and to a lower arm 244 of the actuating lever tends to move the lever in a clockwise direction to effect engagement of the clutch.

The actuating lever 226 is normally restrained from clockwise movement (Fig. 7) by a link 246 one end of which is pivoted at 248 on the lever 226, and the other end 250 of which has a tooth 252 arranged to engage a pawl 254 forming one arm of a bell crank lever 256 pivoted at 258 on the frame. The other arm 260 of the lever 256 has a roll 262 adapted, when the machine is at rest, to engage one or another of the high parts 264 or 265 of the cam 266 carried by a cam shaft 66. The link 246 is positioned in a slot in the pawl 254, and a spring 268 connecting the link 246 and a pin 270 on the frame normally operates to force the link upwardly toward the pawl. There is also provided a stop 272 for limiting counterclockwise movement of the pawl. A spring 275 connecting a pin 273 and the frame tends to force the pawl in a counterclockwise direction (Fig. 7).

In order to release the pawl 254 in initiating engagement of the clutch, there is a control lever 274 pivoted at 276 on the bracket 242 and carrying a link 278 terminating in a latch 280 extending through a slot 282 in the outer end of the link 246 and movable to engage the upper surface of link 246 to depress the link. The link 278 is normally held up out of engagement with the link 246 by a spring 284, upward movement 65 of the link 278 being limited by engagement of a nose 286 on the control lever with a stop 288.

The control lever 274 is arranged to be actuated, in a counterclockwise direction to release the pawl 254, by means of a plunger 290 forming part of a solenoid 292, which is actuated by manually operable means in initiating a power operation of the machine.

When the solenoid is actuated, the plunger 290 moves in a direction to rotate the lever 274

in a counterclockwise direction pulling down the link 278 which causes the latch 280 to release the tooth 252 from the pawl 254 and the spring 240 then causes the lever 226 to move the sleeve 238 to the right effecting disengagement of the brake and causing clutch engagement of the shaft 184 with the flywheel 206. Upon rotation of the drive shaft the cam shaft 66 is rotated to effect operation of the platen as above described.

As the cam shaft rotates the roll 262 drops off the engaged high part 264 of the cam 266 permitting counterclockwise movement of the pawl 254 into position against the stop 272 and behind 252 into position against the tooth 252 on the link 246, which has at this time been moved to the right of its position shown in Fig. 7. After somewhat less than 180° rotation of the cam 266 the roll 262 rides up on the other high part 265 of the cam forcing the lever 256 in a clockwise direction. This causes the pawl again to engage the tooth 252 and to move the link 246 to the left and the lever 226 in a counterclockwise direction resulting in disengagement of the clutch and application of the brake to bring the machine to rest.

Means is provided for adjustment of the position of the high parts 264 and 265 of the cam 266 in order to facilitate the timing of the operation of the link 246. To this end the cam 266 is carried by a plate 294 keyed to the cam shaft 66. The plate is provided with elongated peripheral slots 296 through which extend bolts 298 carried by the cam. The angular position of the cam relatively to the shaft can be adjusted by rotating the cam relatively to the plate and then securing the cam to the plate by means of nuts 300 on the bolts.

Means is also provided for cushioning the engagement of the clutch when the spring 240 causes the lever 226 to move the sleeve 238 to the right in Fig. 5. To this end the yoke 230 is provided with an extension 302 to which is connected a piston 304 extended in an air cylinder 306, pivotally mounted at 308 upon a bracket 310. The cylinder is provided with an air outlet 312 so arranged that, when the piston is urged to the right as when the clutch is engaged, rapid movement of the piston will be prevented.

Power operation of the machine is initiated by manually operable mechanism closely associated with the handle 22 and requiring the use of both hands of the operator in actuating separate switches arranged in series in the circuit through the solenoid 292, as shown in Figs. 9, 10, and 11. One of the switches is a push button switch 314 mounted upon a bracket 315 on the beam. The switch is controlled by a member in the form of a lever 316 pivotally mounted on a pin 318 in a recess 320 in the handle and operable by hand grip 322 secured to the lever. A plunger 324 connected to the lower end of the lever is arranged to actuate the switch 314 when the upper end of the lever is forced toward the axis of the handle by one hand of the operator.

Mounted on a horizontal plunger 326 in a housing 328 on the beam and spaced some distance laterally from the handle are two hand knobs 330 located upon opposite sides of the beam. Either knob can be pushed inwardly to cause the plunger to trip one of the push button switches 332 or 334 which are arranged in series with the switch 314 in the electrical circuit through the solenoid 292. The plunger 326 carries at its central portion a collar 336 pinned to the plunger and

arranged for sliding movement in a sleeve 338. On the plunger are loosely mounted two frusto-conical members 340 located upon opposite sides of the sleeve and normally forced into engagement with the sleeve by springs 342 on the plunger and bearing on the housing and on the outer ends of the members. The members 340 normally lie adjacent to leaf springs 344 which are secured to the housing and have free end portions 345 extending into position adjacent to push buttons 346 of the switches. Outward movement of either of the members 340 results in engagement of the frusto-conical surface of the member with its associated spring to depress the switch button. Thus when one of the hand knobs 330 is forced inwardly the collar 336 moves the member 340 on the far side of the sleeve outwardly effecting operation of the adjacent switch. Upon release of the hand knob springs 342 return the collar and the member to neutral positions thus releasing the switch.

The construction and arrangement of the parts just described are such that the beam can be swung over a die located upon the platen by the use of one hand of the operator, the hand gripping the handle 22 in moving the beam into operative position and the fingers being used for operating the hand grip 322 to actuate the switch 314. The other hand is then used to press one of the knobs 330 effecting an operation of one of the switches 332 or 334 to initiate an operation of the machine. Since both hands of the operator are required for operating the switches at points above the striking face of the beam any likelihood of injury to the hands of the operator through operation of the beam is eliminated.

Mechanism is provided for arresting lateral movement of the beam across the platen after power operation has been initiated. The purpose of this mechanism is to eliminate any tendency of lateral movement of the beam relatively to the die and the work during the pressure applying operation, thus avoiding any likelihood of the die moving along the work in such a way as to produce inaccurate cutting of blanks.

To this end there is provided a band brake 350 (Figs. 12 and 15) extending around the post 18 and arranged to be operated from the cam shaft 66 shortly after the latter commences to rotate. The ends of the brake band are pivotally secured at 352 and 354 on a lever 356 pivotally mounted at 358 on a bracket 360 secured to the frame. The lever is connected to a rod 362 extending to one arm of a bell crank lever 364 pivoted at 366 on a bracket 367 on the frame, the other arm of which is pivotally secured to a vertically extending rod 368 operatively connected to the shaft by means of a ring 370 loosely mounted on the shaft. The ring is held against movement along the axis of the shaft by two pairs of clamping plates 372 and 374 secured to the shaft by screws 376. The ring 370 carries a roll 377 adapted to engage cams 378 carried by the clamping plates 374, the roll being forced upwardly into engagement with the cams by a spring 379 connecting the bracket 360 and the lever 364. Each of the cam members has a roll engaging portion 380 providing a sharp rise terminating in a roll release in the form of a drop off 382. The cams 380 are spaced apart 180° so that the roll engaging portions are effective to engage the roll and move the rod 368 downwardly twice during each revolution of the cam shaft. The cams are mounted on the shaft in such manner that the timing of the roll operation will be to effect movement of the rod shortly after the cam shaft com-

mences to rotate after the pressure applying operation has been initiated. Movement of the roll in a downward direction results in operation of the rod 368 through the bell crank lever 364 to rotate the lever 356 in a clockwise direction (Fig. 15) to apply the brake. This operates to arrest movement of the beam laterally of the platen as the pressure applying operation commences. Shortly thereafter the roll drops off the high part of the cam and effects release of the brake.

The beam 16 is normally movable about the axis of the post by means of the handle 22, and the construction and arrangement are such that the beam can be moved angularly in either direction until it is clear of the platen. In order to prevent further movement which might take the beam out of the reach of the operator stop mechanism is provided. To this end the post is provided with a collar 384 (Fig. 8) which is secured to the post by pin 386. The collar is provided with projecting portions 388 diametrically opposite each other and arranged to engage a stop plate 390 when the post is moved angularly a distance in either direction.

As shown in Fig. 16, the motor 208 is supplied from a three-phase power source comprising power lines 420, 422 and 424 which extend through a magnetic motor starter 426. The starter is provided with three contacts 428, 430 and 432 which, when a coil 434 is energized, close the circuits through the power lines 420, 422 and 424, respectively. A conductor 436 connects the power line 420 with one side of a push button stop switch 438 the other side of the switch being connected by a conductor 440 with one side of a push button start switch 442. The other side of the start switch is connected by a conductor 444 to the coil 434 which is connected to the power line 422. The stop switch is normally closed and the start switch is normally open. When the start switch is depressed current flows through the coil 434 actuating the motor starter to close the contacts 428, 430 and 432 and starting the motor. The coil 434 is maintained energized by a holding circuit which extends from the power line 422 through the coil 434, the conductor 444, and a conductor 446, through a relay 448, a conductor 450, a contact 452 in the motor starter, and a conductor 454 leading to the conductor 440, and thence through the stop switch 438 to the power line 420. The relay 448 has a contact 456 arranged to be closed upon energization of a coil 458. This coil is in a circuit through the secondary 460 of a transformer 462 the primary 464 of which is supplied current from the power lines 420, 422, thus the motor starting contacts are maintained closed and the motor continues to operate until the stop switch is depressed to break the holding circuit. A conductor 466 connected to one side of the transformer secondary extends to one side of a relay 468. The relay has a coil 470 which when energized closes a contact 472 to conduct current from conductor 466 through the solenoid coil 292 and from thence to a conductor 474 leading to the other side of the transformer secondary. Extending from the conductor 466 is a branch circuit leading through the switches 332 and 334 through a coil 476 of a relay 478 and thence to the conductor 474. Another branch circuit extends from conductor 466 through the switch 314 and a coil 480 of a relay 482 and from thence to conductor 474.

When both relays 478 and 482 are energized through closing the switch 314 and

of the switches 332 and 334 current passes from the conductor 466 through contact 484 of relay 478 and through a contact 486 of relay 482 through the coil 470 of relay 468 to conductor 5 474 thus energizing the relay 468, and closing the contact 472 thus effecting operation of the solenoid 292. This initiates a power operation of the machine as heretofore described.

As long as the solenoid 292 remains energized 10 the plunger 290 (Fig. 7) is held inwardly and the link 278 is held down within the slot 282, with the result that the latch 280 is held in inoperative position, thus preventing actuation of the link 246 to produce another power operation of the machine.

Solenoid 292 is maintained in energized condition as long as any one of the switches 314, 332 and 334 is held in closed position. This is accomplished by means of holding circuits to maintain the coil 470 energized with the result that the contact 472 controlling the solenoid circuit is maintained in closed position. If the switch 314 is held closed the coil 480 of the relay 482 is energized as above described and current passes from the conductor 466 through a contact 488 of relay 468 through a conductor 490, through a contact 492 in relay 482, and a conductor 494 to the coil 470 and from thence to conductor 474.

If the switch 314 is open but either of the switches 332 or 334 is closed current passes from conductor 466 through the contact 488 of the relay 468 through the conductor 490, through a contact 496 in the relay 478 which at that time is energized and through a conductor 498, the conductor 494, through the coil 470 and to the conductor 474.

Thus after initial operation of the solenoid 292 in effecting power operation of the machine 40 the solenoid is continued to be energized, through operation of one or another of the holding circuits just described, as long as any of the manually operated switches is held closed. The purpose of this construction and arrangement is to insure the safety of the operator by preventing him from tying back or wedging in closed position one or another of the switches 314, 332, 334, which is sometimes attempted by an operator in order to speed up his production. By the construction above described after an operator has used both hands to initiate the power operation of the machine he must release the manually operable starting controls in order to permit the resetting of the starting mechanism.

The safety control mechanism disclosed herein is claimed in divisional application for United States Letters Patent, Serial No. 324,372, filed December 5, 1952 in our names.

Having described our invention, what we claim as new and desire to secure by Letters Patent of the United States is:

1. In a clicking machine having a beam, a platen for supporting work to be operated upon, means for supporting the platen comprising upper and lower toggle members, pins pivotally securing the members together, and the upper members being pivotally secured to the platen and the lower members being pivotally secured to the frame of the machine, cam controlled means for actuating the toggles in effecting movement of the platen toward and away from the beam, and cam controlled means for rocking the platen about the pins during actuation of the toggles to cause the platen to

2. In a clicking machine, a beam, a platen, means for moving the platen toward and away from the beam comprising a drive shaft, a cam shaft operatively connected to the drive shaft, toggles mounted on the frame of the machine, and pivotally connected to the platen, toggle actuating levers each having one end connected to a toggle, a bracket upon the frame and having a guide slot therein, the other end of each toggle having a pin positioned in the guide slot, a roll carried by each of the pins, and cams upon the cam shaft for engaging the rolls to effect actuation of the toggles in causing operation of the platen, said cams being positioned upon the cam shaft 180° out of phase with each other thereby to effect a rocking of the platen during its movement toward and away from the beam.

3. In a clicking machine, a beam, a platen, means for moving the platen toward and away from the beam comprising a drive shaft, a cam shaft operatively connected to the drive shaft, toggles mounted on the frame of the machine, and pivotally connected to the platen, toggle actuating levers each having one end connected to a toggle, a bracket upon the frame having a guide slot therein, the other end of each toggle having a pin positioned in the guide slot, a roll carried by each of the pins, cams upon the cam shaft for engaging the rolls to effect actuation of the toggles in causing operation of the platen, said cams being positioned upon the cam shaft 180° out of phase with each other thereby to effect a rocking of the platen during its movement toward and away from the beam, a second cam upon the cam shaft, a control lever pivotally mounted upon the frame and carrying a roll in engagement with the second mentioned cam, and a link connecting the control lever and the platen for controlling angular movement of the platen to cause the platen to roll along the beam.

4. In a clicking machine having a work supporting platen, a post positioned at one side of the platen, a beam secured to the post and movable across the platen about the axis of the post, a mounting for the post comprising a nut secured to the frame of the machine, a sleeve making screw thread engagement with the nut, a bearing for the post at the upper end of the sleeve providing for rotation of the post relatively to the sleeve, means for limiting movement of the post heightwise of the sleeve, a spur gear, a ring gear continuously in mesh with the spur gear and movable with the sleeve heightwise of the spur gear, and means for rotating the spur gear, whereby the position of the beam heightwise of the platen is adjusted.

5. A clicking machine comprising a beam, a work supporting platen spaced heightwise of the beam, said platen comprising a body portion having therein a cylindrically curved recess, and a cutting block having oppositely disposed curved faces corresponding in curvature to that of the recess, the cutting block being positioned in the recess with one of its curved faces in engagement with the bottom of the recess, and means for rolling the platen along the beam in producing a pressure applying operation upon work carried by the platen.

6. A clicking machine comprising a beam, a work supporting platen spaced heightwise of the beam, said platen comprising a body portion having therein a cylindrically curved recess, and a removable cutting block having oppositely disposed curved faces corresponding in curvature

to that of the recess, the cutting block being positioned in the recess with one of its curved faces in engagement with the bottom of the recess, and means for moving the platen toward and away from the beam and for rolling the platen along the beam in producing a pressure applying operation upon work carried by the platen.

7. A clicking machine comprising a platen, a vertically extending post at one side of the platen, a beam carried by the post, means mounting the post for angular movement about its axis whereby the beam can be moved across the platen, a brake for arresting angular movement of the post, power means for effecting relative movement of the platen and the beam toward and away from each other to cause a pressure applying operation upon work carried by the platen, and means operable upon initiation of operation of the power means for applying the brake.

8. In a clicking machine, a platen, a post mounted for movement angularly about its axis, a beam secured to the post, a drive shaft, means operatively connecting the drive shaft and the platen, a brake on the post for arresting angular movement of the beam, and means responsive to rotation of the drive shaft for applying the brake immediately after an initiation of a power operation of the shaft.

9. A clicking machine comprising a platen, a vertically extending post at one side of the platen, a beam carried by the post, means mounting the post for angular movement about its axis whereby the beam can be moved across the platen, a brake for arresting angular movement of the post, power means including a drive shaft for effecting relative movement of the platen and the beam toward and away from each other to cause a pressure applying operation upon work carried by the platen, and means operatively connecting the drive shaft and brake to apply the brake when operation of the platen is initiated.

10. In a clicking machine having a platen, a vertical post mounted at one side of the platen for movement about its axis, a beam secured to the post and movable across the platen, and means including a drive shaft for causing relative movement of the platen and beam in effecting a pressure applying operation upon work carried by the platen, a brake for the post, a ring loosely mounted upon the shaft, a link depending from the ring, an operative connection between the link and the brake, members secured to the shaft for preventing movement of the ring axially of the shaft, a roll on the ring, and a cam on one of the members for engaging the roll at a predetermined time in the cycle of operation of the shaft to cause the link to apply the brake.

IN THE NAME OF THE: FRANK E. STRATTON.
IN THE NAME OF THE: HORATIO V. HALL.
